by Edward Wright Atty.

UNITED STATES PATENT OFFICE.

WILLIAM T. LANE, OF BAYSIDE, NEW YORK, ASSIGNOR TO FRANKLIN RAILWAY SUPPLY COMPANY, OF WILMINGTON, DELAWARE, A CORPORATION OF DELAWARE.

FIRE-DOOR APPARATUS.

1,288,619.

Specification of Letters Patent. Patented Dec. 24, 1918.

Application filed March 25, 1918. Serial No. 224,451.

To all whom it may concern:

Be it known that I, WILLIAM T. LANE, a citizen of the United States, residing at Bayside, in the county of Queens and State 5 of New York, have invented a certain new and useful Improvement in Fire-Door Apparatus, of which improvement the following is a specification.

This invention relates to fire door apparatus for locomotive boilers, and more particularly to boilers having large fire door openings with double doors of the so-called "butterfly" type, in which the door plates swing laterally and vertically in opposite 10 directions, one of the objects being to provide an improved motor device for operating either one of the door plates separately and independently of the other. Another object is to provide an improved hand-operated device for opening either door independently.

With these and other objects in view, my invention comprises a certain construction and combination of parts which will now be 15 fully described, the novel features being set forth in the claims.

In the accompanying drawing, Figure 1 is a front elevation of a fire door apparatus embodying my improvement; Fig. 2 a detail 20 view showing a portion of one of the door plates and the cylinder partly in section; and Fig. 3 a transverse sectional view taken on the line 3—3 of Fig. 2.

In locomotive boilers provided with large 25 fire door openings and double doors of sufficient width to allow for delivering fuel through the same into the fire box at either side when only one door is open, it is desirable that the two doors should be independently operable in order that one door 30 may be kept closed at the time of firing and thus prevent the admission of large quantities of cold air to the fire box, while at the same time economizing in the use of 35 power and reducing the wear of the apparatus.

According to the construction shown, a frame 5, is bolted to the back head of the locomotive boiler around the fire door opening, and carries the two pivot bolts 6, and 6^a, on which are mounted the two door plates, 7 and 7^a, which are adapted to swing laterally and vertically and meet together upon a vertical center line when in the normal closed position. A horizontal cylinder

8, is also mounted above the door and contains two pistons 9, and 9^a, at opposite ends of the cylinder, said pistons having pins 10, and 10^a, projecting out through a slot 11, in the cylinder. The doors are provided 60 with arms 12, and 12^a, which are connected by the respective links 13, and 13^a, with the pins of the pistons for operating the doors with fluid pressure, the arm and link being so positioned as to occupy a straight 65 line in the full open position of the door, thereby operating as a cushion to the opening movement in that position.

Manual valve devices 14, and 14^a, may be employed for controlling the fluid supply 70 to and the exhaust from the respective ends of the cylinder, the valves being usually actuated by a well known form of pedal appliance, not shown. By operating one of the manual valves, either right or left as 75 desired, the corresponding door may be opened by fluid pressure admitted to act upon the piston at that end of the cylinder, and then as the fluid pressure is permitted to exhaust the door will be closed by gravity. 80

In order to operate the doors or either of them, by hand two handles 15, and 15^a, are pivotally mounted on the respective bolts or pins 16, and 16^a, on which are also mounted the sleeves 17, and 17^a, and gear segments 18, and 18^a, the latter being arranged to mesh with corresponding gear segments 19, and 19^a, respectively, on the door plates 7, and 7^a. The sleeves are provided with projections 20, and 20^a, for engaging corresponding lugs 21, and 21^a, on the respective segment gears 18, and 18^a. Each handle is connected with its respective sleeve so as to have a relative lateral movement to provide for co-operation with the 95 usual notches of its respective quadrant 22, or 22^a, as will be readily understood.

When one of the doors is operated by fluid pressure the gear segment is turned in such direction that the lug 18 moves away from 100 the projection 20 of the sleeve 17, so that the handle remains stationary in its notch upon the quadrant. When it is desired to open the door by hand, the handle is pulled down and the projection on the sleeve engages the lug on the gear segment so as to 105 rotate the same with it, and by means of the intermeshing gears the door is swung up on its pivot to its open position, as indicated in dotted lines.

When it is desired to shovel coal onto the fire at either side of the firebox, for instance at the left hand side, the valve device 14^a, is opened by the fireman in the usual way, thus admitting compressed air from the supply pipe to the pipe leading to the left hand end of cylinder 8, where it actuates the piston 9^a, to move the pin 10^a, and link 13^a, connected to the lug 12^a, of the door 7^a, and causing the door to swing upward on its pivot 6^a, to the open position, indicated in dotted lines in Fig. 1. The door 7, at the other side in the meantime remains closed and prevents the admission of cold air through that side of the firebox while the fireman is delivering coal through the door at the left hand side. When he has delivered the coal through said door and wishes to close the same he releases the valve device permitting the same to close, thus shutting off the supply of fluid to the cylinder and opening the exhaust port 23, for allowing the fluid to exhaust from the cylinder and the door to close by gravity.

It will now be seen that by means of my improvement either one of the door plates may be operated separately and independently of the other, and either by fluid pressure or by hand, as desired.

Having now described my invention, what I claim as new and desire to secure by Letters Patent, is:

1. In a fire door apparatus, the combination of two door plates mounted to swing laterally and vertically in opposite directions and adapted to cover the furnace opening, a horizontal cylinder above said doors, two pistons at opposite ends of said cylinder, and a mechanical connection from each piston to one of said doors for operating the same independently.
2. In a fire door apparatus, the combination, of two door plates pivotally mounted to swing laterally and vertically in opposite directions, a horizontal cylinder above the

door, two pistons in said cylinder, each door plate having an arm extending above its pivot, and a link connecting each piston with one of said arms.

3. In a fire door apparatus, the combination with two door plates mounted to move in opposite directions, a fluid pressure cylinder, two pistons at opposite ends of said cylinder, connections from said pistons to the respective door plates, and independent manually operated valves for controlling the supply of fluid to the opposite ends of said cylinder.

4. In a fire door apparatus, the combination of a door plate pivotally mounted to swing laterally and vertically, a cylinder and piston for operating said door, a handle mounted on a pivot separate from that of the door plate, and a connection actuated by the movement of the handle for manually operating the door.

5. In a fire door apparatus, the combination of a door plate pivotally mounted to swing laterally and vertically, a cylinder and piston for operating said door, a handle mounted on a pivot separate from that of the door plate, a gear segment carried by the door, another gear segment meshing with the first and mounted on the pivotal axis of the handle, and means actuated by the handle for turning said gears.

6. In a fire door apparatus, the combination of a door plate pivotally mounted to swing laterally and vertically, a cylinder and piston for operating said door, a handle mounted on a pivot separate from that of the door plate, a sleeve operated by the handle and provided with a projection, a gear segment carried by the door, and another gear segment meshing therewith and having a lug engaging the projection on the sleeve.

In testimony whereof I have hereunto set my hand.

WILLIAM T. LANE.
